UNITED STATES PATENT OFFICE.

MAX W. GOLDBERG, OF BRILLION, WISCONSIN.

LADLE-HOLDER.

1,110,049.

Specification of Letters Patent.

Patented Sept. 8, 1914.

Application filed May 23, 1914. Serial No. 841,426.

To all whom it may concern:

Be it known that I, MAX W. GOLDBERG, a citizen of the United States, and resident of Brillion, in the county of Calumet and State of Wisconsin, have invented new and useful Improvements in Ladle-Holders, of which the following is a description, reference being had to the accompanying drawings, which are a part of this specification.

10 The invention relates to ladle-holders.

It frequently happens in the foundry that molds of different heights have to be poured and while it is customary to transport the ladle with the metal therein from the furnace to the molds by an overhead conveyer such as a traveling crane it is necessary in view of the varying heights of the molds to adjust the height of the ladle for pouring after it has been brought to the molds.

20 It is one of the objects of this invention to provide a ladle holder which permits of the raising or lowering of the ladle carried by it to facilitate the pouring of the metal from the ladle for molds of different heights.

25 Another object of the invention is to provide a ladle holder in which the ladle may be raised or lowered and adjustably secured in different positions.

The invention further designs to provide 30 a new and improved form of ladle holder.

In the drawings, Figure 1 is an elevation of the device embodying the invention. Fig. 2 is a section taken on the line 2—2 of Fig. 1. Fig. 3 is a section taken on the line 35 3—3 of Fig. 1. Fig. 4 is a section taken on the line 4—4 of Fig. 1.

The invention comprises a frame A having vertical side members B and C and a transverse upper member D, the lower ends 40 of the members B and C having hooks E thereon adapted to be detachably secured on the handles F and G on the ladle H and means are provided for raising and lowering the frame A and consequently the ladle 45 H which is secured to it and for adjustably securing said frame in different positions to raise or lower the ladle to facilitate the pouring of the metal from the ladle for molds of different heights.

50 The frame A is adjustably secured on a tubular supporting member I which is adjustably secured at its upper end to a tubular support J fitting within it, said tubular support J carrying a hook K at its upper 55 end which is designed to be detachably secured to an overhead means for conveying

the ladle. The means for adjustably securing the support I to the support J for extending the length of the support for the holder comprises a plurality of apertures *p* 60 in the support P which register with apertures *j* in the support J adapted to receive a locking pin which extends therethrough such as the staple *k*.

A transverse member L is riveted at its 65 end to the sides B and C of the frame and carries intermediate of its ends a tubular guide M which is designed to slidably fit within the tubular support I. The tubular support I carries a collar N at its lower end secured thereto by a set screw *n* and a block or a collar O fits upon the outside of the support I and rests upon the collar N. A vertically-extending rack P is secured at one end 70 to the collar O and at its other end to a collar Q which is rigidly secured to the upper end of the support I by a set screw *q*. Thus it will be noted that the collar Q and rack P serve to anchor the collar O on the support I adjacent the lower end thereof. 75

The means for raising and lowering the frame A comprises an operating lever 10 keyed at one end to a shaft 11 which is pivotally mounted in the collar O and a pair of arms or levers 12 which are also keyed 80 to the shaft 11, the lever 10 and the arms 12 connected to the shaft 11 forming a bell crank lever. The other ends of the arms 12 are pivotally and adjustably secured by a bolt 13 extending therethrough to one end 85 of a pair of arms or levers 14 which are pivotally secured at their other ends to a pin 15 which is pivotally secured in the transverse member D of the frame A. The pin 15 carries an anti-friction roller 16 which is designed to operatively engage with the outside of the support I, the pin 15 being journaled in side members 17 and 18 of the frame member D and the roller 16 being secured on the pin between these sides. The 90 arms 12 and 14 are provided with a series of apertures 19 through which the bolt 13 passes for adjustably securing said arms, as previously pointed out, and the arms 12 each carry projecting lugs or stops 20 which engage with the sides of the arms 14 when the frame is in raised position as shown in dotted lines in Fig. 1.

95 Means are provided for locking the frame A in adjusted position to prevent downward movement thereof comprising a dog 21 which engages the toothed rack P at one 100

end and which is keyed to a pin 23 which is journaled in the sides 17 and 18 of the frame member D the pin 23 carrying a lever 22 keyed thereto adjacent one side of the 5 frame member D.

The operation of the device is as follows: The ladle holder is hooked on to the overhead support or conveyer for instance the hook K may be secured to the cable of an 10 overhead traveling crane and the ladle which is filled with molten metal is then secured to the frame A by the hooks E which engage the handles G and F of the ladle. In this 15 condition the ladle is transported to the molds. If it be desired to vary the height of the ladle for pouring molds of different heights, the lever 10 is operated to either raise or lower the supporting frame A by means of the lift-linkage comprising the lever 10, arms 12 and 14, for, it will be apparent that when the lever 10 is moved down the arms 12 will move up and will exert an upward force on the arms 14 which being secured to the transverse member D of the 20 frame will raise the frame, the roller 16 moving upwardly upon the support and the guide M moving upwardly within the tubular support I and when the desired position has been reached the locking dog 21 is 25 thrown into engagement with the rack P by means of the lever 22 in which position the handle G of the ladle H may be operated to tilt the ladle to pour the mold.

The invention thus exemplifies a portable 30 ladle holder in which the ladle may be raised or lowered with respect thereto for pouring molds of different heights.

The invention is not to be restricted to the details herein set forth but may be 40 varied so as to be within the scope of the appended claims.

What I claim as my invention is:

1. A portable ladle holder comprising a portable support, means comprising an extensible sleeve for adjusting the length of 45 said support, a ladle holding frame mounted on said support, and means for raising and lowering said frame on said support.

2. A portable ladle holder comprising a 50 portable support, supporting means comprising a telescoping member adjustably secured to said support, a ladle holding frame mounted on said support, means for raising and lowering said frame on said support 55 and means for securing said frame in raised or lowered position on the support.

3. A portable ladle holder comprising a 60 portable support, a ladle holding frame mounted on said support, a plurality of levers pivotally mounted on said support, a plurality of levers pivotally mounted on said frame and pivotally secured to the levers on said support and means for operating 65 the levers on said support and frame to raise or lower the frame on the support.

4. A portable ladle holder comprising a support, a ladle holding frame slidably mounted on said support, means for guiding the frame, a plurality of levers pivotally mounted on said support, a plurality of levers pivotally mounted on said frame and pivotally secured to the levers on said support and means for operating the levers on the support and frame to raise or lower the frame on the support. 70

5. A portable ladle-holder comprising a portable support, a ladle holding frame slidably mounted on said support, means for raising or lowering said frame on said support, a rack rigidly secured to said support, 80 a locking dog pivotally secured to said frame for engagement with the rack to lock the frame against downward movement on the support.

6. A portable ladle holder comprising a portable support, a ladle holding frame mounted on said support, a guide on said frame movable within said support, a guide on said frame movable on the outside of said support, and means for raising or lowering 90 said frame on the support. 85

7. A portable ladle holder comprising a portable support, a ladle holding frame slidably mounted on said support, a guide on said frame movable within said support, a 95 roller guide on said frame movable on the outside of said support, and means for raising or lowering said frame on the support.

8. A portable ladle holder comprising a portable support, a ladle holding frame slidably mounted on said support, means for guiding the frame on the support, a bell crank lever pivotally secured to the support and a lever or arm pivotally secured to said lever and said frame for raising or lowering 105 the frame on the support.

9. A portable ladle holder comprising a support, a ladle holding frame slidably mounted on said support, a plurality of levers pivotally mounted on said support, a 110 plurality of levers pivotally mounted on said frame and pivotally secured to the levers on said support, means for operating the levers on the support and frame to raise or lower the frame on the support and means for locking the frame to the support in raised or lowered position. 115

10. A portable ladle holder comprising a support, a ladle holding frame slidably mounted on said support, a plurality of levers pivotally mounted on said support, a plurality of levers pivotally mounted on said frame and pivotally and adjustably secured to the levers on said support and means for operating the levers on the support and frame to raise or lower the frame on the support. 120

11. A portable ladle holder comprising a support, a ladle holding frame mounted on said support, a plurality of levers pivotally 125

- mounted on said support, a plurality of levers pivotally mounted on said frame and pivotally secured to the levers on said support, means for operating the levers on the support and frame to raise or lower the frame on the support and a stop on the levers pivotally secured to the support for limiting the movement of the levers in one direction.
- 19 12. A portable ladle holder comprising a portable support, a ladle holding frame slidably mounted on said support, a bell-crank lever pivotally secured to the support, and a lever or arm pivotally and adjustably secured to said lever and pivotally secured to 15 said frame for raising or lowering the frame on the support.
- In testimony whereof, I affix my signature, in presence of two witnesses.

MAX W. GOLDBERG.
